UNITED STATES PATENT OFFICE.

FRED E. MYERS, OF JOPLIN, MISSOURI, ASSIGNOR TO THE MEEKER COMPANY, OF JOPLIN, MISSOURI, A CORPORATION OF MISSOURI.

DESIGN FOR LEATHER.

Application filed March 21, 1925. Serial No. 12,812. Term of patent 3½ years.

To all whom it may concern:

Be it known that I, FRED E. MYERS, a citizen of the United States, residing at the city of Joplin, county of Jasper, and State of Missouri, have invented a new, original, and ornamental Design for Leather, substantially as shown, of which the following is a specification, reference being had to the

accompanying drawing, forming part thereof which shows a piece of leather constituting my design.

I claim:

The ornamental design for leather, substantially as shown.

FRED E. MYERS.
